UNITED STATES PATENT OFFICE.

PAUL H. HORWITT, OF BROOKLYN, NEW YORK, ASSIGNOR TO INDEPENDENT PAPER MILLS, INC., OF BROOKLYN, NEW YORK, A CORPORATION OF NEW YORK.

DESIGN FOR A DISPENSER FOR PAPER PRODUCTS.

Application filed December 30, 1925. Serial No. 15,903. Term of patent 14 years.

To all whom it may concern:

Be it known that I, PAUL H. HORWITT, a citizen of the United States, residing at the borough of Brooklyn, in the county of Kings, city and State of New York, have invented a new, original, and ornamental Design for a Dispenser for Paper Products, of which the following is a specification, reference being had to the accompanying drawing, forming part thereof.

The drawing is a perspective view of the article showing my new design.

I claim:

The ornamental design for a dispenser for paper products, as shown.

PAUL H. HORWITT.
